5 Claims. (Cl. 88—24)

1

This invention concerns improvements in or relating to copy-holders and printing frames for photo-process copying equipment. A common type of copy-holder incorporates a main frame within which the copy is releasably held under a hinged cover; and the copy-holder is mounted at opposite sides on trunnions for swivelling movement between the vertical position where the copy is displayed before the camera or light source, and a horizontal position for loading and unloading of the copy within the holder when the hinged cover is raised.

In a modification of the last construction, instead of hingedly securing the cover to the copy-holder, it is made as a separate part, which is adapted to be releasably clamped to the copy-holder in such a way that, when the copy-holder is in a horizontal position, the cover is capable of being lifted bodily clear of the copy-holder so as to give clear access thereto for insertion and removal of the copy.

The present invention is concerned with the last type of construction of copy-holder in which the cover is adapted to be lifted clear of the copy-holder.

The main object of the invention is to provide improved supporting means for holding the cover during the lifting and lowering operation relatively to the copy-holder.

According to the present invention there is provided, for a copy-holder of the type described, means for supporting its cover in a horizontal position so as to enable it to be raised and lowered relatively to the copy-holder, comprising a body having a pair of spaced recesses adapted 30 releasably to receive projections at a side of the cover, a bolt carried by the body for movement in and-out of the position for locking each of the projections or both of the projections in their recesses, so as to secure the cover to the body and retain it in the horizontal position and a plunger carried by the body for operating each or both bolts.

In a convenient construction, the plunger member is constituted by a portion of a liftable standard for raising and lowering the cover above a stationary copy-holder mounted for swivelling movement about a horizontal axis between vertical and horizontal positions. Thus the body may be mounted for the sliding movement on one or more standards, or extensions thereof, in such a way that it is capable of limited vertical movement between a locking position at which the bolt or each bolt is in a locking position and a release position at which the bolt or each bolt is released from its locking position.

2

It is preferred to operate a bolt from a plunger through the medium of a cam. In a convenient construction, one end of the bolt is formed as a catch for co-operating with one of the recesses 5 and the other end of the bolt is formed with an oblique cam face for engagement by a thrust element such as a roller on a stud, which is carried by the plunger for movement transverse to the bolt, so that movement of the plunger in its guide in one direction acts to thrust the bolt to its locking position through inter-engagement of the thrust element and cam face. Spring means may resiliently hold the bolt in an inoperative position.

15 In the preferred construction, the cover of the copy-holder is adapted to be raised and lowered in a horizontal position by two pairs of standards, disposed at opposite sides of the cover, adapted to be raised and lowered by a suitable driving mechanism so as to raise and lower the cover. At the upper ends of each pair of standards is fitted supporting means having the construction already described, with a body portion of elongated shape extending horizontally and formed 20 with vertical guides for a pair of upstanding plunger rods projecting from the upper ends of the standards, each such plunger rod being fitted with a thrust member adapted to engage the cam surface at the inner end of a bolt mounted in a guide for horizontal movement, the outer end of the bolt being adapted to serve as a catch for co-operating with a recess adjacent to the end of the body for receiving a projection in the form of a pin or peg fitted to the adjacent side of the cover.

25 One construction of this device in accordance with the present invention will now be described by way of example with reference to the accompanying drawings in which:

30 Figure 1 is a side elevation of a lifting head, with a portion of a cover plate broken away in order to show the internal construction;

35 Figure 2 is a plan view taken on a line 2—2 of Figure 1;

40 Figure 3 is a side elevation of the right-hand portion of the device shown in Figure 1 with the moving parts in an alternative position; and

45 Figure 4 is an elevation, to a smaller scale, showing the manner in which the cover turns with the copy-holder after release of the holding device.

50 The copy-holder is shown in chain lines at 10, and its cover at 11. The copy-holder is fitted centrally at opposite sides with trunnions 12 fitted in bearing blocks 13 so as to be capable of swivelling movement about the horizontal axis of the

two trunnions, in the manner shown in Figure 4. In this way the copy-holder 10 and its cover 11 can be swung from a vertical position, in which the copy is displayed before the camera, or light source to a horizontal position at which the copy can be inserted in or removed from the copy-holder. To gain access to the interior of the copy-holder, the cover 11 is lifted bodily clear of the copy-holder, as shown by arrows in Figure 4, the copy-holder 10 remaining stationary in a horizontal position.

Raising and lowering of the cover 11 is effected by a pair of standards or vertical shafts 14 disposed at each side of the copy-holder. The shafts 14 are fitted for sliding movement in a suitable frame or casing 15, being operated by an electric motor through gearing or other suitable mechanism (not shown). Across the upper ends of each pair of shafts 14 is fitted a lifting head adapted releasably to be secured against the adjacent side of the cover 11. The lifting head is of elongated form and it incorporates a body portion 16 of dished formation over which is fitted a cover plate 17. This cover plate is located by pins 18 and secured by socket-headed screws 19. The back wall of the body 16 is formed with two spaced vertical guides 20 which are a sliding fit over upstanding extensions 21 of rod-like form on the upper end of the shafts 14. Threaded into each shaft extension 21 is a stud 22 that projects through a slot 23 in the guide 20. On the outer end of the stud is fitted a roller 24.

The body 16 is formed with two horizontal guide-ways 25 in each of which is fitted a bolt 26 in the form of a plate. The inner ends of these bolts adjacent the rollers 24 extend obliquely so as to form cam faces 27. Each cam face 27 of the bolt 26 is held resiliently in contact with the roller 24 by means of a compression spring 28 fitted within a rectangular recess 29 in the bolt. One end of the spring 28 bears against an end of the recess, and the other end is engaged in the head 30 of an anchor bolt 30 secured to the back wall of the body 16.

At its two outer ends the cover plate 17 is formed with recesses 30, 31 for receiving pins or studs 32 fitted laterally to the adjacent side of the copy-holder cover. It will be seen that the recess 30 opens upwardly and the recess 31 opens downwardly. Heads 33 on the pins or studs 32 project into the body of the head 16 in the path of the bolts 26. At their outer ends the bolts are of curved formation as shown at 34, so as partially to embrace the heads 33 at the open sides of the recesses 30, 31 when the bolts are in the locking position shown in Figure 3. In this way the bolts then act to retain the pins or studs 32 within the recesses. When it is required to turn the copy-holder from a horizontal to a vertical position, as shown by the arrows in Figure 4, the various parts will be in the position shown in Figure 1, in which the bolts are retracted so as to leave the pins or studs 32 to swing out of them as the cover 11 turns with the copy-holder 10. Suitable clamping means are provided for holding together the copy-holder 10 and its cover 11.

For raising the cover 11 when the copy-holder 10 is in a horizontal position, the driving mechanism is operated to elevate the pairs of shafts 14 at the sides of the copy-holder. During the initial movement of the shafts 14, the upstanding extensions 21 will be free to slide in the guides 20 of the body 16, until the collars 35 on the shafts engage bosses 36 on the bottom of the body 16, as shown in Figure 3. As the result of the ex-

tension 21 thus sliding in their guides, the rollers 24 move up the slots 23 and right along the cam faces 27, so thrusting the bolts 26 against the resilient pressure of the springs 28, outwardly towards the ends of the body 16. The catch portions 34 at the outer ends of the bolts then move to a locking position for retaining the pins or studs 32 within the recesses.

With continued upward movement of the lifting shaft 14, the cover 11 is lifted bodily upwards clear of the copy-holder 10, and it is locked securely in a horizontal position by reason of the body 16 and cover plate 17 of the lifting head remaining seated through their weight on the collars 35.

During the return movement of the lifting shafts 14, the lifting heads remain seated on the collars 35 until the cover 11 rests on the copy-holder 10. Further downward movement of the shafts brings the collars 35 clear of the lifting heads, to the position shown in Figures 1 and 4, during which final stage the rollers run down the slots 23 in order to permit the retraction of the bolts 26 under the action of the springs 28. The pins or studs 32 are then free to move out of the recesses 30, 31.

I claim:

1. For a copy-holder of the type described in photo-process copying equipment, means for supporting the cover of the copy-holder in a horizontal position so as to enable the cover to be raised and lowered relatively to the copy-holder, comprising the combination of a body mounted for limited vertical sliding movement on vertical extensions serving as plungers at the upper ends of a pair of vertical shafts capable of axial movement for raising the cover through the body, a pair of recesses opening respectively upwards and downwards spaced apart horizontally and disposed adjacent to the ends of the body for releasably receiving pins or pegs projecting from the adjacent side of the copy-holder cover, a pair of bolts mounted for horizontal sliding movement in the body, each bolt having its outer end shaped to project over one of the pins or pegs on the cover so as to lock it in its recess, a spring acting resiliently to withdraw each bolt from its locking position, and a thrust pin or roller on each plunger portion of the shaft held by a spring in engagement with an oblique cam face on the inner end of the bolt, in such manner that sliding movement of the plunger relatively to the body acts through the thrust pin or roller and cam to slide the bolt to a locking position.

2. For a copy-holder of the type described in photo-process copying equipment, means for supporting the cover of the copy-holder in a horizontal position so as to enable the cover to be raised and lowered relatively to the copy-holder, comprising two bodies mounted at opposite sides of the cover on the upper ends of vertical shafts guided for axial movement to raise and lower the cover relatively to the copy-holder, a pair of spaced recesses in each body opening respectively upwards and downwards, and spaced apart horizontally for releasably receiving projections on the adjacent side of the cover when the latter is in a horizontal position, releasable means for locking the projections in their recesses so as to secure the cover in a horizontal position on the bodies, and release means operated by the vertical shafts on their reaching a lowered position when the cover rests on the copy-holder for releasing the locking means and thereby permit-

ting the projections on the cover to move out of the recesses to enable the cover to be swivelled with the copy-holder on its trunnions into a vertical position.

3. Supporting means as claimed in claim 2, wherein the locking means for the projections comprises a bolt slidably fitted on the body and associated with each recess, said bolt being movable between a locking position where it overlies the recess to withhold the projection and to a release position.

4. Supporting means as claimed in claim 3, wherein each part is provided with an oblique cam engaged by a thrust member carried by an extension of the shaft for moving the bolt to its locking position.

5. For a copy-holder of the type described in photo-process copying equipment, means for supporting the cover of the copy-holder in a horizontal position so as to enable the cover to be raised and lowered relatively to the copy-holder, comprising the combination at each of two opposite sides of the cover of a body mounted for limited vertical sliding movement on vertical extensions serving as plungers at the upper ends of a pair of vertical shafts capable of axial movement for raising the cover through the body, a pair of recesses opening respectively upwards

and downwards spaced apart horizontally and disposed adjacent to the ends of the body for releasably receiving pins or pegs projecting from the adjacent side of the copy-holder cover, a pair of bolts mounted for horizontal sliding movement in the body, each bolt having its outer end shaped to project over one of the pins or pegs on the cover so as to lock it in its recess, a spring acting resiliently to withdraw each bolt from its locking position, and a thrust pin or roller on each plunger portion of the shaft held by a spring in engagement with an oblique cam face on the inner end of the bolt, in such manner that sliding movement of the plunger relatively to the body acts through the thrust pin or roller and cam to slide the bolt to a locking position.
